UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

BUTTON-ATTACHING MACHINE.

1,348,229.

Specification of Letters Patent. Patented Aug. 3, 1920.

Application filed February 26, 1918. Serial No. 219,315.

To all whom it may concern:

Be it known that I, BERNARD T. LEVEQUE, a citizen of the United States, residing at Wenham, in the county of Essex and State 5 of Massachusetts, have invented certain new and useful Improvements in Button-Attaching Machines; and I do hereby declare the following to be a full, clear, and exact description of the invention, such as will 10 enable others skilled in the art to which it appertains to make and use the same.

The invention relates to machines for sewing on buttons, and more particularly to machines in which each button is attached 15 by a plurality of superposed stitches.

Machines of this type as heretofore constructed have been automatically stopped after each button is attached to permit the operator to feed the succeeding button into 20 attaching position, or to feed the work into position for the attachment of the succeeding button. It is the primary object of the present invention to provide a machine of this type which will operate to automatically 25 attach and space a series of buttons, thereby increasing the rapidity with which the buttons may be attached, with a corresponding increase in the production of the machine.

To this end a feature of the invention contemplates the provision in a machine in which the stitch forming mechanism attaches each button by a series of superposed stitches of mechanism for automatically 30 presenting successive buttons in attaching position, and for automatically spacing the work between successive button attaching cycles. These mechanisms may be of any suitable construction which is adapted to 35 coöperate with the stitch forming and other mechanisms of the machine. In order, however, to increase the rapidity with which a series of buttons may be attached, a further feature of the invention is preferably utilized in spacing the work. This feature 40 consists in the provision of mechanism for automatically spacing the work during that period in the reciprocation of the needle when it is clear of the work. The work 45 may therefore be spaced while the stitch forming mechanism continues to run at its normal speed, the movement of the work taking place after the needle clears the work 50

on its back stroke at the completion of one button attaching cycle, and then the needle 55 enters the work on its forward stroke to begin the succeeding button attaching cycle. This reduces the interval between the completion of one sewing cycle and the beginning 60 of the next to a minimum. This feature of the invention is not confined in its application to a button sewing machine, but may be embodied with advantage in other machines in which a predetermined series or group of stitches is used in each of a 65 plurality of successive sewing cycles.

The various features of the invention will be readily understood from an inspection of the accompanying drawings and the following detailed description of the machine 70 illustrated therein.

In the drawings, Figure 1 is a side elevation of a machine for attaching shank eyed buttons embodying all the features of the invention in their preferred forms; Fig. 2 75 is a front elevation of the machine; Fig. 3 is a detail section in plan view showing parts of the work spacing mechanism; Fig. 4 is a detail end view of the work spacing roll; and Fig. 5 is a detail view showing the manner 80 in which the needle thread is withheld from the shuttle during the reciprocation of the needle in which the work is spaced.

The invention is shown as embodied in a machine for attaching shank eyed buttons 85 by a series of superposed lock stitches which in many respects is similar in construction to the machines shown in Patents Nos. 1,149,474, August 10, 1915, and 1,151,735, August 31, 1915. In this machine the shank 90 eyed buttons are fed successively from the lower end of a button chute 2 into attaching position in the presser foot 4 by a reciprocating button carrier 6 similar in construction to the button carrier of Patent 95 No. 1,149,474. The button carrier is secured at the forward end of a bar 8 and is automatically advanced and retracted at proper times during the operation of the machine by a cam 10 secured to the cam shaft 12 and 100 engaging the upper end of a lever 14 the lower end of which is connected by a link 16 with the rear end of the bar. The forward end of the bar is supported on a vertical link 18. The presser foot is secured 105 on the lower end of a vertically movable

spring pressed bar 20 and during the sewing clamps the work against the work supporting face of the throat plate 22. When the machine is stopped the presser foot is 5 lifted through the levers 24 and 26 operated from the stop mechanism 28 as in said patents.

The stitch forming mechanism comprises a vertically reciprocating and laterally jogging needle 30 and a cooperating shuttle 32. 10 The needle bar 34 is mounted in a frame 36 which is supported on pivot screws 3 and is so oscillated that the needle passes alternately through and outside of the button 15 eye. The frame is thus oscillated through a lever 40 one end of which is connected by a link 42 with the frame and the other end of which carries a roll engaging a cam groove 44 which is formed in a cam disk 46 20 secured to the cam shaft 12. The needle is reciprocated by a crank 48 mounted on the end of the driving shaft 50 and connected with the needle bar by a link 52. The shuttle is carried on the end of a shaft 54 which 25 is driven from a crank 56 on the driving shaft through the link 58 and the usual connections indicated at 60.

The machine is provided with a thread 30 cutter and holder which is automatically operated to sever and hold the needle thread at the completion of each button attaching cycle. The thread holder and cutter is similar to the thread holder and cutter of Patent No. 1,151,735 and comprises a thread 35 cutting and gripping bar 62 mounted to reciprocate in a guide way 64 formed in the presser foot. The cutter and holder bar 62 is advanced and retracted at the proper intervals during the operation of the machine through a bell crank lever 66 one arm 40 of which is connected by a link 68 with the bar and the other end of which carries a roll 70 arranged to engage a cam groove 45 formed in one of the cam disks secured to the cam shaft 12.

The mechanism for automatically spacing the work after each button has been attached and the needle thread has been severed and held comprises a spacing or feeding roll 72 50 arranged to underlie the presser foot directly back of the work supporting face of the throat plate. This roll is normally below and out of contact with the under surface of the work. When the work is to be 55 spaced the roll is raised and presses the work upward against the presser foot, raising the presser foot so that it no longer clamps the work against the throat plate. As the roll lifts the work and presser foot 60 the rotation of the roll also feeds the work forward, the distance through which the work is advanced depending upon the interval during which the roll supports the work and presser foot. In the construction shown 65 the feed roll is mounted upon the forward

end of a shaft 74 the rear end of which carries a bevel gear 76 engaging a similar gear on the lower end of a shaft 78. The upper end of this shaft is connected with the driving shaft through bevel gears 80 so that continuous rotary movement is imparted to the feed roll. The rear end of the feed roll shaft 74 is journaled in a bracket 82 which is pivoted to the frame so that the forward end of the shaft may be raised and lowered. 70 The forward end of the shaft is journaled in a bearing sleeve 84 which is supported on the forward end of an arm 86 secured to a rock shaft 88. 75

The mechanism for rocking the shaft 88 80 to raise and lower the feed roll at the proper intervals during the operation of the machine comprises a vertically reciprocating bar 90 arranged to be moved into position to engage and depress a vertical rod 92, the lower end of which is pivotally connected to an arm 94 on the rock shaft. The feed roll and rod 92 are held in normal position by a spring 93. The bar 90 is given a uniform reciprocation and the upper end of the rod 92 carries an adjustable contact sleeve 96 which may be vertically adjusted to vary the interval during which the feed roll is raised by the downward stroke of the bar 90. The lower end of the bar 90 slides through a bearing sleeve 98 which is provided with a lateral pivot engaging a bearing in the lower end of a carrier lever 100 and retained therein by a washer secured to the end of the pivot by a screw, as clearly indicated in Fig. 100 2. The upper end of the bar surrounds an eccentric 102 formed on a continuously rotating shaft 104. The shaft 104 is driven from the driving shaft through bevel gears 106 so that it is continuously driven and makes one 105 revolution for each revolution of the driving shaft. The bar 90 is, therefore, advanced and retracted during each reciprocation of the needle bar and in timed relation thereto. The bar is normally held out of position to 110 engage the contact sleeve 96 by a spring 108, the position of the carrier lever 100 and bar 90 being determined by the engagement of a roll 110 on the bar with the periphery of the cam disk 46. When the work is to be 115 spaced a cam projection 112 rides under the roll and swings the bar 90 into position above the contact sleeve 96, this movement of the bar taking place when the bar is at the upper end of its stroke and just as the needle emerges from the upper side of the work. During the next forward or downward stroke of the bar it engages the upper end of the contact sleeve 96 and depresses the rod 92, thus raising the feed roll so that 120 it will act to advance and space the work. The interval during which the roll is raised and the distance through which the work is spaced will depend upon the adjustment of the contact sleeve 96, the vertical position of 125 130

which will determine the interval during which the bar 90 will retain the roll in raised position.

- The maximum interval during which the feed roll may act is the interval between the disengagement of the lower end of the needle from the work and its reengagement therewith and the speed of the feed roll is such that the maximum feed or spacing which may be desired will be effected within such interval. To enable the work to be advanced by the feed roll during the major portion of this interval means is provided for preventing the engagement of the needle loop by the shuttle during that reciprocation of the needle in which the work is to be advanced by the feed roll. The needle will, therefore, during this reciprocation merely carry a needle loop down through the work and then withdraw it from the work and the advance of the work may begin immediately after the needle has cleared the work and without waiting for the needle thread to pass around the shuttle and to be drawn up by the take-up. This manner of handling the needle thread is of special importance in case a thread cutter and holder is employed for severing and holding the thread at the end of the button attaching cycle. In such case the thread cutter and holder may be operated to sever and hold the thread after the needle has been retracted and the last button attaching stitch completed and set since during the next reciprocation of the needle the thread leading from the thread holder and cutter to the eye of the needle will merely be carried down through the work and then withdrawn therefrom by the needle. The means shown for preventing the engagement of the shuttle with the needle loop comprises a thread controlling finger 114 arranged to engage the needle thread between a thread guiding loop 116 which is secured to the needle bar and a thread guiding loop 118 which is secured to the frame 36. The thread leads from the needle eye back of the guide 116, in front of the controller finger 114, and back of the guide 118 to the take-up 120 which is of the usual construction and is operated from the cam 122 on the driving shaft. The thread controlling finger 114 is formed by the horizontal arm of a rod 124 which is secured in one arm of a lever 126. The other arm of the lever is slotted to engage a pin in the forward end of a lever 128, the rear end of which carries a roll 130 arranged to ride on the periphery of the cam disk which is secured to the cam shaft 12. The cam disk is provided with a cam projection 132 arranged to rock the lever 128 and swing the thread controller 114 forward, as indicated in Fig. 5, and thus hold the needle thread taut before the needle starts upward and prevent the throwing out of the usual

loop to be entered by the point of the shuttle.

Assuming the parts to be in the positions which they occupy when the machine is stopped the mode of operation in attaching a series of buttons is as follows: The work is placed in position over the throat plate and feed roll and then the machine is started by depression of the starting treadle which is connected to the stop mechanism through the usual rod 134. The movement of the stop mechanism releases the lever 26 so that the presser foot clamps the work against the throat plate. The movement of the stop mechanism also shifts the driving belt on to the driving shaft so that the shaft is operated and through the worm 136 and worm wheel 138 transmits motion to the cam shaft 12. During the first down stroke of the needle it is positioned to pass outside the button eye and at this time there is no button in position in the presser foot. During the first up stroke of the needle the button carrier moves forward and feeds a button into position in the presser foot so that it is in position for the passage of the needle through its eye during the second downward stroke of the needle. During the continued rotation of the cam shaft 12 the needle passes alternately through and outside of the eye of the button, thus forming a group or series of superposed stitches the number of which will depend upon the form of the cam groove 44 and the number of rotations of the driving shaft required to turn the cam shaft through a single revolution. During the sewing the thread cutter and holder bar 62 is advanced to open the thread cutter and holder at a time when the needle is positioned to pass through the button eye. During the latter part of the sewing after a sufficient number of stitches have been sewed to retain the button in position the button carrier is retracted preparatory to feeding forward the succeeding button in the button chute. The cam groove 44 is so shaped that after making its last reciprocation through the eye of the button the needle passes through the work at the usual point outside the eye and then during its next reciprocation passes through the work at a slightly increased distance from the eye and then again passes through the work at the usual distance outside the eye. As the needle completes its reciprocation at the abnormal distance outside of the eye and after the stitch thus formed has been tightened by the take-up the thread cutter and holder is operated to cut and hold the end of the needle thread. During the next reciprocation of the needle which as before stated is through the work at the usual normal distance outside the button eye, the thread controller finger acts to prevent the throwing out of a loop by the needle so that

the thread leading from the thread holder and cutter to the eye of the needle is merely carried down through the work and then withdrawn without being engaged by the shuttle. After the needle emerges from the work during this reciprocation, and before it again enters the work, the bar 90, which has been swung into active position, acts to raise and lower the feed roll to unclamp, 5 space, and reclamp the work without interrupting the reciprocation of the needle. The bar 90 then returns to normal inactive position, and the cycle of operations is repeated. So long as the starting rod remains depressed, therefore, the buttons will be automatically fed and attached and the work 10 spaced while the sewing mechanism continues to run at its normal speed. When the desired number of buttons have been attached the starting rod is released so that it is free to rise, and the machine will be stopped at the completion of an attaching and spacing cycle by the stop mechanism, the movement of which into active position 15 is controlled by a timing lever 140. One end of the lever carries a roll 142 arranged to ride on the periphery of a controlling cam which is secured to the cam shaft 12 and is provided with a depression into 20 which the roll may pass when the parts are 25 in the position indicated in Fig. 1.

While it is preferred to employ the specific construction and arrangement of parts shown and described, particularly in embodying the invention in the type of machine shown and described in the patents above referred to, it will be understood that this construction and arrangement is not essential to the broader features of the invention, and may be varied or modified as 30 found desirable or best suited to the construction and mode of operation of the machine in which it is to be embodied.

What is claimed is:—

- 45 1. A sewing machine having, in combination, stitch forming mechanism including a uniformly reciprocating needle, mechanism for actuating the same to sew a predetermined group of stitches in each of a succession of sewing cycles, and mechanism for automatically shifting the work during a reciprocation of the needle between successive cycles to secure an unstitched space between successive groups of stitches.
- 50 2. A sewing machine having, in combination, stitch forming mechanism including a uniformly reciprocating needle, mechanism for actuating the same to sew a predetermined group of stitches in each of a succession of sewing cycles, and mechanism for automatically shifting the work during a reciprocation of the needle between successive cycles to secure an unstitched space between successive groups of stitches ad- 55 justable to vary the spacing.

3. A sewing machine having, in combination, stitch forming mechanism including a uniformly reciprocating needle, mechanism for actuating the same to sew a predetermined group of stitches in each of a 70 succession of sewing cycles, mechanism for severing the thread at the end of each sewing cycle, and mechanism for spacing the work during a reciprocation of the needle.

4. A sewing machine having, in combination, stitch forming mechanism including a uniformly reciprocating needle and a loop taker, mechanism for actuating the same to sew a predetermined group of stitches in each of a succession of sewing cycles, mechanism for preventing the taking of the loop by the loop taker during the reciprocation of the needle following the completion of the group, and mechanism for spacing the work before it is again entered by the 85 needle.

5. A sewing machine having, in combination, stitch forming mechanism including a uniformly reciprocating needle and a loop taker, mechanism for actuating the same to 90 sew a predetermined group of stitches in each of a succession of sewing cycles, means for severing and holding the thread at the completion of the group, mechanism for preventing the taking of the loop by the 95 loop taker during the succeeding reciprocation of the needle, and mechanism for thereafter spacing the work before it is again entered by the needle.

6. A sewing machine having, in combination, stitch forming mechanism comprising a reciprocating needle and a loop taker, and mechanism for preventing the taking of the needle loop by the loop taker and for spacing the work after a predetermined series 105 of stitch forming cycles.

7. A sewing machine having, in combination, stitch forming mechanism, and mechanisms acting automatically at intervals, including a plurality of stitch forming 110 cycles, to release, space and reclamp the work and to feed buttons successively into attaching position.

8. A sewing machine having, in combination, stitch forming mechanism, a work 115 clamping presser foot, a button carrier for feeding buttons successively to the presser foot, mechanism for automatically lifting the presser foot and spacing the work after a predetermined number of stitch forming 120 cycles, and mechanism for automatically operating the button carrier between successive button attaching and spacing cycles.

9. A sewing machine having, in combination, stitch forming mechanism, means for 125 presenting buttons in attaching position, and mechanisms for cutting and holding the thread and for automatically spacing the work between button attaching cycles.

10. A sewing machine having, in combi- 130

nation, mechanism for automatically presenting buttons in attaching position, stitch forming mechanism for forming successive groups of superposed button attaching stitches, and mechanism for automatically spacing the work between groups.

11. A sewing machine having, in combination, a presser foot, a button carrier for feeding buttons to the presser foot, a reciprocating and laterally vibrating needle, a co-operating shuttle, mechanism for actuating the needle and shuttle to form groups of superposed button attaching stitches, mechanism for automatically spacing the work between groups, and mechanism for automatically actuating the button carrier.

12. A sewing machine having, in combination, mechanism for automatically presenting buttons in attaching position, stitch forming mechanism for forming successive groups of button attaching stitches including a uniformly reciprocating needle, and mechanism for spacing the work between groups during a return and forward stroke of the needle.

13. A sewing machine having, in combination, stitch forming mechanism comprising a needle and loop taker, means for presenting buttons in attaching position, means for severing and holding the needle thread after a predetermined series of stitch forming cycles, mechanism for withholding the needle thread from the loop taker during the succeeding forward stroke of the needle,

and mechanism for spacing the work during the return and next succeeding forward stroke of the needle.

14. A sewing machine having, in combination, stitch forming mechanism, a presser foot, a feed roll underlying the presser foot, normally inactive mechanism for raising and lowering the feed roll during a single cycle of the stitch forming mechanism, and mechanism for rendering the roll raising and lowering mechanism active at intervals including a plurality of stitch forming cycles.

15. A sewing machine having, in combination, stitch forming mechanism including a reciprocating needle, a presser foot, a feed roll underlying the presser foot, mechanism for raising the feed roll including a bar reciprocating in time with the needle, and mechanism for rendering the bar active at intervals including a plurality of stitch forming cycles.

16. A sewing machine having, in combination, stitch forming mechanism including a reciprocating needle, a presser foot, a feed roll underlying the presser foot, a rod connected to raise and lower the roll, a bar reciprocating in time with the needle, and mechanism acting at intervals to move the bar during a single reciprocation into and out of position to engage and operate the rod.

BERNARD T. LEVEQUE.
